US0D1061949S

(12) **United States Design Patent** (10) **Patent No.:** **US D1,061,949 S**
(45) **Date of Patent:** **** Feb. 11, 2025**

(54) **PEDESTAL FOR ROOF-MOUNTED EQUIPMENT**

- (71) Applicant: **Timothy M. Graboski Revocable Trust**, Deerfield Beach, FL (US)
- (72) Inventor: **Timothy Michael Graboski**, Deerfield Beach, FL (US)
- (73) Assignee: **Timothy M. Graboski Revocable Trust**, Deerfield Beach, FL (US)
- (**) Term: **15 Years**
- (21) Appl. No.: **29/848,446**
- (22) Filed: **Aug. 2, 2022**

Related U.S. Application Data

- (63) Continuation of application No. 17/740,171, filed on May 9, 2022, now Pat. No. 11,725,777, and a continuation of application No. 29/837,866, filed on May 9, 2022, now abandoned, which is a continuation of application No. 16/592,472, filed on Oct. 3, 2019, now Pat. No. 11,326,736, said application No. 17/740,171 is a continuation of application No. 16/592,472, filed on Oct. 3, 2019, now Pat. No. 11,326,736.

CLAIM

The ornamental design for a pedestal for roof-mounted equipment as shown and described.

DESCRIPTION

FIG. 1 is a front elevation view of a pedestal for roof-mounted equipment.

FIG. 2 is a top plan view thereof;

FIG. 3 is a rear elevation view thereof;

FIG. 4 is a bottom plan view thereof; and,

FIG. 5 is a side elevation view thereof.

The drawings contain symbolic break lines. The portion between the break lines forms no part of the claimed design.

1 Claim, 3 Drawing Sheets
